US00D983058S

(12) **United States Design Patent** (10) Patent No.: **US D983,058 S**
(45) Date of Patent: **** Apr. 11, 2023**

(54) **DIAGNOSTIC TESTING APPARATUS FOR AUTOMOBILES**

(71) Applicant: **Autocom Diagnostic Partner AB**, Trollhättan (SE)

(72) Inventor: **Martin Sallander**, Gothenburg (SE)

(73) Assignee: **AUTOCOM DIAGNOSTIC PARTNER AB**, Trollhättan (SE)

(**) Term: **15 Years**

(21) Appl. No.: **35/512,450**

(22) Filed: **Jun. 14, 2021**

(80) **Hague Agreement Data**

Int. Filing Date: **Jun. 14, 2021**

Int. Reg. No.: **DM/215929**

Int. Reg. Date: **Jun. 14, 2021**

Int. Reg. Pub. Date: **Aug. 27, 2021**

(30) **Foreign Application Priority Data**

Dec. 29, 2020 (EM) 008373328-0001

(51) **LOC (14) Cl.** **10-04**

(52) **U.S. Cl.**

USPC **D10/78**

(57) **CLAIM**

The ornamental design for a diagnostic testing apparatus for automobiles, as shown and described.

DESCRIPTION

The patent or application file contains at least one drawing executed in color. Copies of this patent or patent application publication with color drawing(s) will be provided by the Office upon request and payment of the necessary fee.

1. Diagnostic testing apparatus for automobiles

1.1 is a rear view.

1.2 is a side view.

1.3 is a front perspective view.

1.4 is a top view.

1.5 is a side view.

1.6 is a bottom view.

1.7 is a front view.

**1 Claim, 7 Drawing Sheets
(7 of 7 Drawing Sheet(s) Filed in Color)**
